US00D469462S

(12) **United States Design Patent**
Onodera et al.(10) Patent No.: **US D469,462 S**
(45) Date of Patent: **** Jan. 28, 2003**(54) **HEATER LAMP UNIT FOR FIXING TONER
IN AN IMAGE FORMING APPARATUS**5,787,319 A * 7/1998 Tomatsu 399/33
5,842,098 A * 11/1998 Ueno et al. 399/322
6,097,904 A * 8/2000 Tsuruno et al. 399/33
6,181,898 B1 * 1/2001 Sato 399/103
6,229,120 B1 * 5/2001 Jewell ..... 219/486(75) Inventors: **Ken Onodera, Ibaraki (JP); Shuho
Yokokawa, Ibaraki (JP); Sho
Sawahata, Ibaraki (JP)**(73) Assignee: **Hitachi Koki Co., Ltd., Tokyo (JP)**(**) Term: **14 Years**(21) Appl. No.: **29/132,833**

JP 2-21667 2/1990

(22) Filed: **Nov. 17, 2000**

(57) **CLAIM**(51) LOC (7) Cl. **16-03**The ornamental design for a heater lamp unit for fixing toner
in an image forming apparatus, as shown.(52) U.S. Cl. **D18/40****DESCRIPTION**(58) Field of Search **D18/36, 40, 43,**FIG. 1 is a perspective view of the top, front and one end of
the heater lamp unit for fixing toner in an image forming
apparatus showing our new design;**D18/56; 219/486; 250/325; 399/33, 100,**

FIG. 2 is a top plan view thereof;

103, 122, 186, 320, 322

FIG. 3 is a side elevational view of one side thereof;

(56) **References Cited**

FIG. 4 is a bottom plan view thereof;

U.S. PATENT DOCUMENTS

FIG. 5 is an end elevational view of an opposite end thereof;

3,324,291 A * 6/1967 Hudson 250/325
3,875,407 A * 4/1975 Hayne 399/100
3,891,846 A * 6/1975 Ito 399/100
4,063,810 A * 12/1977 Mailloux 399/100
D350,974 S * 9/1994 Inoue et al. D18/40
5,450,174 A * 9/1995 Osbourne et al. 399/186
5,572,307 A * 11/1996 Tomatsu et al. ..... 399/122FIG. 6 is an end elevational view of said one end thereof;
and,

FIG. 7 is a side elevational view of an opposite side thereof.

The invention is shown broken away to indicate indeterminate length.
